DESIGN FOR A VALISE OR SIMILAR ARTICLE

Richard H. Arbib, Huntington Woods, Mich., assignor to United States Rubber Company, New York, N. Y., a corporation of New Jersey

Application December 9, 1947, Serial No. 143,059

Term of patent 14 years

(Cl. D87—5)

To all whom it may concern:

Be it known that I, Richard H. Arbib, a citizen of the United States of America, residing in Huntington Woods, county of Oakland, and State of Michigan, have invented a new, original, and ornamental Design for a Valise or Similar Article, of which the following is a specification, reference being had to the accompanying drawing, forming part thereof, wherein:

Fig. 1 is a side view of a valise or similar article embodying the design, the handles being shown raised.

Fig. 2 is an end view of the valise shown in Fig. 1.

Fig. 3 is a view similar to Fig. 1, except that the handles are depressed.

Fig. 4 is a top view of the valise shown in Fig. 3; and

Fig. 5 is a bottom view thereof.

I claim:

The ornamental design for a valise or similar article, substantially as shown.

RICHARD H. ARBIB.
